DESIGN FOR AN OIL DISPENSER

John F. Carter, Bryan, Ohio, assignor to The Aro Equipment Corporation, Bryan, Ohio, a corporation of Ohio

Application May 28, 1934, Serial No. 51,944

Term of patent 7 years

To all whom it may concern:

Be it known that I, JOHN F. CARTER, a citizen of the United States and a resident of Bryan,
in the county of Williams and State of Ohio,
have invented a certain new, original, and ornamental Design for an Oil Dispenser, of which the following is a specification, reference being had to the accompanying drawing, forming part thereof.

Figure 1 is a plan view of an oil dispenser showing my new design.

Figure 2 is a front elevation of the same.

I claim:

The ornamental design for an oil dispenser
substantially as shown.

JOHN F. CARTER.
